FRANTZ ADOLF MARTENS, OF COPENHAGEN, DENMARK.

GLUING DEVICE FOR UNITING WARP THREADS.

Application filed September 11, 1922. Serial No. 587,629.

To all whom it may concern:

Be it known that I, FRANTZ ADOLF MARTENS, subject of the King of Norway, residing at Copenhagen, Denmark, have invented certain new and useful Improvements in Gluing Devices for Uniting Warp Threads, of which the following is a specification.

For the purpose of joining old and new warp threads in textile factories it has been proposed to stretch the old and new warp above one another between beams, in such a manner that each warp forms two parts crossing one another, and in such a manner that the crossing of the two warps are disposed one below the other between the same warp beams on which there is provided, on either side of the crossing points of the warp parts, a gluing device adapted to slide 20 at right angles to the warps. On top of said gluing device the warp threads are moved in pairs by means of a cam disc, the so-called heart, reciprocating between the warp beams and, alternately on either side 25 of the crossing points, engaging simultaneously one thread of the old warp and one thread of the new one and pushing them above a glue-squirting opening on the top side of the adjacent gluing device, where 30 the point of contact between the threads is moistened by an adhesive agent squeezed drop-wise out from the glue container.

The details of the manner of action and construction of this apparatus appear from 35 my co-pending application Serial No. 411280 filed September 18, 1920.

In gluing apparatus a small pressure pump has heretofore been used as a glue squirting member. The pump must frequently be inspected and cleaned, as inevitably a small portion of the glue becomes solidified in the pump, the consequence being that not always the same quantity of glue is pushed forward by each piston-stroke made by the pump. The main point is, however, to supply neither too much nor too little glue during each individual gluing operation but, as far as possible, always exactly the same quantity, i. e. one drop. As long as the glue container is approximately full of glue, and as long as no solidified particles of glue are present in the pump, the latter will act with sufficient accuracy, but when the quantity of glue is reduced, for instance after a long period of operation, the pump may press a smaller quantity of

glue forward for each piston stroke, and, as mentioned above, solidified glue may render the action of the pump irregular. Furthermore, according to my co-pending application, the glue container is not absolutely air-tight, the consequence being that in the course of time solidified particles of glue will be formed in the glue container, and the latter must therefore quite frequently be inspected and cleaned.

Another drawback in the above mentioned apparatus is that the glue-moistened threads, which are picked up by a catching wheel on the drying apparatus and moved under a jet of drying air, very easily become accumulated in an irregular manner behind the catching wheel after having been released by the latter, a circumstance seriously interfering with the action of the entire apparatus.

According to the present invention, the said drawbacks are remedied by the provision, immediately behind the catching wheel, of a worm on which the catching wheel deposits the glue-jointed threads which are then, by the rotation of this worm, moved uniformly away from the gluing apparatus. Since the glue squirting member is in the shape of an arm which is rotatable about a horizontal axis in the glue container, and whose surface upon which the glue is carried is larger than the width of the arms, and thus by being swung upward towards the inner side of the cover of the gluing apparatus, the large portion acts in a similar manner as a shovel and lifts a certain quantity of glue up against the said inner side, where the arm remains stationary for a moment thereby squeezing, through a narrow opening in the said cover, one drop of glue. Owing to capillary action in the narrow glue squirting opening, never more than one drop of glue is squeezed out on top of the warp threads held in position above the said opening.

In the drawing, in which the same reference characters indicate like parts throughout,

Figure 1 shows the gluing device in side elevation,

Fig. 2 the same in top-view, and

Fig. 3 a vertical section of the glue container.

The gluing device consists of a box-shaped frame 1 in which there is provided a heating body 2 journaled on a horizontal

shaft 3 supporting, outside of the frame, a catching wheel 4 and a bevel gear wheel 5 behind the catching wheel. In the gluing apparatus there is also inserted a glue container 6, from which, as further mentioned below a drop of glue may be pressed out through a narrow opening 7 in the cover 8 of the frame, the said cover tightly closing the gluing device with the exception of 10 the opening 7. The cover is not shown in Figures 2 and 3.

In the glue container 6 there is journalled an arm 10 pivoted on a horizontal shaft 9 and adapted to be moved by means of two 15 rods 11 and 13, interconnected by means of a link 12. The rod 11 is pivoted on a shaft 14 and rod 13 is pivoted on a shoulder 15 of rod 10.

On the frame there is provided an arm 20 16 pivoted on a vertical pin 17, the said arm being actuated by a cam disc, not shown, in the manner described in my co-pending application above mentioned, so that while the said disc is moving towards 25 the gluing apparatus the said arm will be swung down towards the latter about the pin 17. During this motion of the arm 16, the latter tightens a spring 18 one end of which is thrust against the same, and 30 moves towards the right a rod 19, see Figure 2, said rod being mounted on the side of the frame. A finger on the arm 16 is pivotally connected to a lug 20 on the rod 19. During this motion of the rod 19, a 35 sleeve or the like 21 turns an arm 22 to the right said arm being attached to the shaft 14 outside of the frame, whereby the rods 11 and 13 and, thereby, also the arm 10 swings upwardly as in Figure 1. The free 40 end of the arm 10, which is entirely immersed in glue in the vessel 6 is thereby moved upwards along a guiding surface 23 towards the inside of the cover 8, whereby 45 the said wide shovel-shaped end of the arm 10, see Figure 2, transports a quantity of glue. The guiding surface 23 prevents the glue from flowing away from the arm 10 before the latter reaches the position shown 50 by dot-and-dash lines in Figure 1, during which position of the arm the glue is held pressed momentarily against the inside of the cover 8. The rod system 11, 12, 13 is 55 guided by a suitably shaped guiding surface 25 in such a manner that the arm 10 for a moment remains stationary in its upper position below the cover 8, before its return motion commences owing to the arm 16 being released by the cam disc, and a spring 26 then withdrawing the arm 11. 60 The moment during which the arm 10 is stationary in the said raised position is determined by the shape of the guiding surface 25, so that a drop of glue will have time 65 to flow out through the opening 7 in the cover 8. The diameter of the opening 7

determines the size of the drop squeezed out, but the diameter of the opening 7 may in all cases be chosen so small that capillary action will prevent more than one single drop of glue from penetrating through the 70 said opening during each upward stroke of the arm 10.

The drop of glue which is pressed out through the opening 7 is absorbed by the two warp threads 27, Figure 1, which are above this opening, and have been conveyed to the said opening by the cam disc in the manner specified in my co-pending application, and then during a subsequent motion of the cam disc towards the arm 16 80 these threads are moved on the catching wheel 4, where the threads 27 are caught by the teeth of the said wheel and become exposed to a jet of air from the spout 28 for drying the glue. 85

The threads picked up by the catching wheel are deposited one by one from the catching wheel on a worm 29, which is located immediately behind the catching wheel, and which is driven from the gear 90 wheel 5, by means of a bevel gear drive 30 and a shaft 31 journaled on the sides of the frame 1. The gear wheel 5 rotates together with the catching wheel owing to the spring 18 during the return stroke of 95 the arm 16 forcing the rod 19 to the left, whereby a tappet on the rod 19 turns a lever 32, 33, in clockwise direction, which is journaled on the shaft 3, whereby a pawl 34 pivoted at the end of the arm 32 and engaging a pawl wheel 35 on the shaft 3 rotates the latter, and thereby drives the catching wheel, forward a suitable distance. The threads deposited by the teeth of the catching wheel on the threads of the worm 105 29 will gradually be moved to the right by the rotation of the worm, and pass away from the catching wheel. 110

From the spout 28, a pipe 36 extends over the top of the worm the lower side of which is fitted with very fine openings through which air is blown from the air spout 28 onto the jointed warp threads resting on the worm. The supply of air to the air blowing device and the construction of the 115 latter are mentioned in my co-pending application.

I claim as my invention:

1. In apparatus for gluing together the threads of old and new warps stretched between beams, comprising a glue container having a cover, said cover having a fine opening therein for gluing two threads; a heating body on which the glue-moistened threads are dried; further drying means comprising air spouts; and a catching wheel comprising a worm wheel for conveying the threads from the heating body past the last named drying means. 120

2. In apparatus for gluing together the 125

threads of old and new warps stretched between beams comprising a frame; a gluing device mounted in said frame; a heating device mounted on said frame; a drying device associated with said frame; means for carrying the glue moistened threads to the heating device; and a worm wheel for carrying the threads from the heating device past said drying device.

3. In apparatus for gluing together the threads of old and new warps comprising a frame; a gluing device mounted in said frame and provided with a cover having a small opening therein, said gluing device having an arm pivoted at one end in said device, means in said device for swinging said arm upward through the glue so that the free end will press glue against the cover and press the glue through said opening, and a guiding surface for said free end of the arm; a heating device mounted on said frame; a drying device associated with said frame; and means for carrying the glue moistened threads from the glue cover to said drying device.

4. In apparatus for gluing together the threads of old and new warps comprising a frame; a gluing device having a cover, said cover being provided with a small opening through which glue may be forced; a heating device on said frame adapted to heat the glue moistened threads; a catching wheel on said frame; an air spout adapted to dry said threads; a worm adapted to receive said threads from said catching wheel; and additional drying means for further drying the threads while being carried along by said worm.

5. In apparatus for gluing together the threads of old and new warps comprising a vessel containing glue; an arm pivoted in said vessel and having its free end wider than the remainder of the arm; means for actuating said arm; a guiding surface to prevent the glue from flowing from the wide end of said arm; and means for limiting the amount of glue to be used in gluing the threads.

In testimony whereof I affix my signature.
FRANTZ ADOLF MARTENS.
